HENRY W. GOODRICH AND WILLIAM B. MASON, OF BOSTON, MASSACHUSETTS.

Letters Patent No. 64,305, dated April 30, 1867.

IMPROVEMENT IN STEAM-ENGINE SLIDE-VALVES.

The Schedule referred to in these Letters Patent and making part of the same.

TO ALL WHOM IT MAY CONCERN:

Be it known that we, H. W. GOODRICH and W. B. MASON, both of Boston, in the county of Suffolk, and State of Massachusetts, have invented an Improvement in the Slide-Valves of Steam Engines; and we do hereby declare that the following, taken in connection with the drawings which accompany and form part of this specification, is a description of our invention sufficient to enable those skilled in the art to practise it.

The object of this invention is to lessen the pressure which acts to force the face of the valve upon its seat, by a transfer of the pressure to a carriage mounted on rolls in such a manner that the valve is free at all times to find its seat or to adjust itself on its seat without reference to or control by the relation of the rolls to the track or surfaces upon which they run, the invention being intended for an improvement over that construction of slide-valves in which the valve itself rests and traverses upon rollers, these having a definite and fixed relation between their peripheries, the track on which they roll, the valve-seat, and valve-face, which relation is very difficult of correct adjustment, and when once established is disturbed by the natural process of wear which it is impossible to avoid. In the drawings—

Figure 1 represents, in plan, an embodiment of my invention; while

Figure 2 is a section taken in the line *z z* seen in fig. 1.

a denotes, say for example, the main steam chest of a marine engine, which has a separate exhaust chest. *b* is the valve-seat within the chest, and *c c* denote the location of the ports which convey the steam into the cylinder at either end. The valve *d* is represented as a plain slide without exhaust passages, admitting steam and cutting it off at its ends under movement imparted through the valve-rod *e*. On this valve is fixed a short cylinder, *i*, truly bored to receive a closely fitting piston, which may be packed like any pump or engine piston. This piston is secured to a cross-bar, *g*, over it, and which rests on a frame, *h*, said frame being mounted on rollers or wheels *k* journaled to the frame, and which traverse on the valve-face or on any suitable bearing surface in the steam chest. It will now be seen that the only necessary connection between the valve and the frame is that which obtains by presence of the piston *f* in the cylinder *i*, and that the valve and frame will both move together, whether the valve-rod is directly connected to the one or to the other. To avoid, however, undue wear and strain on the piston *f* and cylinder *i*, we prefer to connect the valve *d* and frame *h* by links *j j*, through which the thrust and pull of the valve-rod can be exerted, the manner of connecting the links being such as will freely permit vertical movements of the valve and frame with respect to each other. It will now be obvious that upon whatever theory the pressure upon slide-valves generally is calculated, a large portion of the area of valve *d* is protected by piston *f* from pressure, said piston itself receiving a pressure which would otherwise operate directly on the valve itself, and being fixed to the cross-beam *g*, said pressure is transferred to the frame *h*, and thereby to the rollers *k*, so that a large part of the pressure, which, but for the arrangement of the valve-cylinder *i* and the piston *f*, would have been exerted to create friction between the valve-face and the valve-seat, is exerted on the journals of the rollers *k*, thus saving unnecessary wear of the valve and its seat and expenditure of power, it taking far less power, under a given load or pressure, to move the parts partly on rolls, than it would to move them entirely as sliding surfaces. By the described arrangement it is obvious that some of the area of the valve is exposed to pressure; the amount of this area may be varied by the designing engineer to suit the requirements of any case, it being of advantage to have pressure enough on the valve to keep it firmly on the valve-seat. Wear of the valve-face, or of the valve-seat, or of the journals, or the peripheries of the trucks, or the rollers, will, it is obvious, have no other effect than a slight relative change of position between the piston *f* and the back of the valve *d*. To relieve the cylinder from presence of water and steam which might collect therein, and so prevent relative movement between the cylinder and its piston, we propose to provide the cylinder with a pipe, located parallel with the valve-stem and working through a stuffing-box in the steam chest. Through this pipe all the possible leakage will have an outlet, and tight packing of the piston is rendered unnecessary.

We claim the combination of a slide-valve, a cylinder, a piston, and a carriage, arranged to operate together, substantially as described.

HENRY W. GOODRICH,
WILLIAM B. MASON.
